ELECTRIC CONNECTER

Harold J. C. Pearson, Atlanta, Ga.

Application July 21, 1932, Serial No. 623,862
Renewed December 21, 1933

7 Claims. (Cl. 173—268)

The invention relates to electric connectors and has as an object the provision of means to connect separate conductors electrically to the respective conduction elements of a concentric cable.

It is a further object of the invention to provide a connector for connecting separate conductors to the successive layers of a cable, wherein the conducting elements are arranged in layers about a central conductor, having means to clamp the expanded ends of the separate concentric conducting layers of the cable to metallic sleeves, which sleeves are provided with means for connection thereto of the separate conductors.

Further objects of the invention will appear from the following description when read in connection with the accompanying drawings showing illustrative embodiments of the invention and wherein:

Fig. 1 is a longitudinal central section;
Fig. 2 is a transverse section on line 2—2 of Fig. 1;

Fig. 3 is an end view seen from the left of Fig. 1 with the cable omitted;

Fig. 4 is a central longitudinal section of a connecting sleeve;

Fig. 5 is an end view of the connector without the casing, seen from the right in Fig. 1;

Fig. 6 is a central longitudinal section of a modified form, and

Fig. 7 is a section on line 7—7 of Fig. 6.

As shown in Fig. 1 the cable to which the connector is to be applied comprises a central conductor 10 and concentric layers of conducting material 11 and 12. The said layers may be in the form of metallic tubes or as shown may be made up of a plurality of wires forming an annular or tubular layer of the cable.

As shown in Figs. 1 to 5 inclusive the conductor comprises an insulating body 13 having a central passage 14 to receive the conductor 10 which may pass therethrough and to which a separate conductor may be soldered.

To connect the layer 11 of the cable with a separate conductor 15 there is shown a metallic sleeve 16 having screwthreaded engagement 17 with a second sleeve 18, which second sleeve is received upon the insulating body 13 and abuts a shoulder 19 thereon. A block 20 is shown as provided with a socket 21 for reception of the conductor 15, which block is shown as secured to the sleeve 18 by means of a screw 22. The end of the body 13 is shown as tapered and the expanded end of the concentric conductor 11 is clamped between the said tapered end of the

insulating body and the interior of the sleeve 16 by virtue of the screw threads 17.

A second hollow insulating body 23 is shown engaged over the sleeve 16, which body is also provided with a conical or tapered end 24 and the insulating body 23 receives thereover a metallic sleeve 25 which abuts the body 23 at a shoulder 26. The metallic sleeve 25 is shown as provided with a block 27 having a socket 28 for the reception of the separate conductor 29. The block 27 is shown as secured to the sleeve 25 by means of a screw 30.

To clamp the expanded end of the layer 12 of the cable against the insulating body 23 there is shown a metallic sleeve 31 having interiorly screwthreaded engagement at 32 with the sleeve 25, by virtue of which screwthreaded engagement the sleeve 31 may be drawn tightly into clamping engagement with the expanded end of layer 12. The sleeve 31 shown in detail in Fig. 4 has a screwthreaded tapered end portion 33 which end portion is slotted as shown at 34, which slotted portion may be clamped upon the exterior of the cable by means of a complementary threaded solid ring 35.

To cover the connector there is shown a cylindrical casing 36 having an end opening at 37 for reception of the cable and a closure at 38 formed with openings 39, 40 and 40' for passage of the central conductor 10 of the cable and for the separate conductors 15 and 29. The closure 38 is shown as screwed into the interior of the opening end of the casing 36.

In application of the connector, the casing 36 is first slipped onto the cable, and then the sleeves 35 and 31 are slipped over the end of the cable from which the insulation and conductors are cut back progressively, until the shoulder of 31 meets the uncut outer braid, as shown in Fig. 1. Then the sleeve 35 is screwed onto 31 over the split ends, by means of screwthreads 33, compressing these to clamp onto the outer braid and securely anchoring this unit of the connector to the cable.

Sleeve 25, carrying a wedge shaped insulating sleeve 23 and a conducting ring 16, is then slipped over the cable and sleeve 25 is screwed onto 31 by means of screwthreads 32, forcing the sleeve 23 into the layer of insulation beneath the outer layer of conductors 12 and forcing these conductors out against the shoulder of sleeve 31, making electrical connection from 12 to 31 and 25. At the same time the insulating sleeve 23 is forced between conductors 11 and 12, preventing any accidental contact.

5 Sleeve 18, carrying a wedge shaped inner insulating sleeve 13 is next slipped over the cable and sleeve 18 is screwed into 16 by means of the screwthreads 17, forcing the wedge shaped insulator 13 under the layer of conductors 11, and clamping it up against 16 making electrical contact between 11, 16 and 18.

10 Provision is made on 25 and 18 to fasten conductors 29 and 15, by means of lugs as shown, 10 clamps, or otherwise, so that the conductors 29 and 15 can be run to terminals or other points. The middle conductor 10, is extended through the hole 40 in sleeve 38 to afford connection to the inner conductor 10.

15 Conductors 15 and 29 are soldered into lugs 20 and 27 and passed through holes 39 and 40' in 38. Sleeve 36 is now brought in position over the connector and screwed onto 38, completing the assembly.

20 In the form of the invention in Figs. 6 and 7 there is shown a central conductor 10 and the concentric layers 11 and 12. In this form of the invention an insulating tube 39 covers the central conductor 10 and receives upon its exterior a metallic sleeve 40" having a connector screw 41' for attachment of a separate conductor thereto. The expanded end of the layer 11 is clamped against the sleeve 40" by means of screws 41 taking into an insulating body 42. The expanded end of the layer 12 is in turn clamped between the insulating body 42 and a metallic sleeve 43 provided with a connector screw 44 for attachment of a second separate conductor, screws 45 being provided for clamping the sleeve 43 against the end of the conductor 12.

25 A casing 46 is shown and a closure member 47 which may be provided with openings not shown for the passage of the separate conductors 15 and 29.

30 The assembly of the structure of Figs. 6 and 7 will be obvious.

35 Minor changes may be made in the physical embodiments of the invention within the scope of the appended claims without departing from the spirit of the invention.

40 I claim:

1. A connector for concentric electric cables comprising, in combination: a plurality of sleeves having successively larger interior diameters to receive successively increased portions of the cable; alternate sleeves of electrical conducting material with a sleeve of insulating material therebetween; screw means to clamp the expanded ends of concentric layers of conductors between said insulating and conducting sleeves; and means to connect separate conductors to said conducting sleeves.

45 2. A connector for concentric electric cables comprising, in combination: a plurality of sleeves having successively larger interior diameters to receive successively increased portions of the cable; opposed ends of said sleeves having complementary frusto conical surfaces to wedge successive layers of conductors therebetween; alternate sleeves of electrical conductive material with a sleeve of insulating material therebetween; screw means to clamp the expanded ends of concentric layers of conductors between said insulating and conducting sleeves and means to connect separate conductors to said conducting sleeves.

50 3. A connector for concentric electric cables comprising, in combination: a body of insulation having a central passage to receive the central conductor of the cable; an end of said body

55 formed to abut the expanded end of an annular conductor; an annular metallic sleeve to surround the central conductor and its insulation and to abut the said expanded end; screw means to clamp said sleeve against said conductor end; and means to electrically connect a separate conductor to said sleeve.

60 4. A connector for concentric electric cables comprising, in combination: a metallic sleeve having a central passage to receive the central conductor of the cable; means to insulate said sleeve from said conductor; screw means to clamp said sleeve against the expanded end of a concentric conductor; a second metallic sleeve to surround said concentric conductor; insulation means between said sleeves; screw means to clamp a second concentric conductor against said second sleeve; and means to electrically connect separate conductors to said respective metallic sleeves.

65 5. A connector for concentric electric cables comprising, in combination: an insulating sleeve having an interior diameter to receive an axial conductor of the cable, and a frusto conical end surface; a metallic sleeve upon said first named sleeve adjacent said end surface; a second metallic sleeve having an inner complementary frusto conical surface in an end thereof and having screwthreaded engagement with the first named metallic sleeve whereby to clamp the expanded end of a concentric conductor between said surfaces and means to connect a separate conductor to one of said sleeves.

70 6. A connector for concentric electric cables comprising, in combination: an insulating sleeve having a central opening to receive an axial conductor of the cable and a frusto conical end surface; a metallic sleeve bearing screw threads on its periphery, seated on said insulating sleeve; a conductor clamping sleeve having interior screw threads and an interior frusto conical surface to clamp the expanded end of a concentric conductor between said surfaces; a second insulating sleeve having a minimum internal diameter to receive said concentric conductor and its insulation, an enlarged portion to receive said clamping sleeve and a frusto conical end surface; a metallic sleeve seating on and projecting from said last named frusto conical end in an interiorly screwthreaded portion; a metallic sleeve having peripheral threads to engage said projecting threaded portion, and a frusto conical interior end portion to clamp a second expanded end of a concentric conductor; said last named sleeve slotted at its remaining end and formed exteriorly with a tapered thread portion and adapted to receive the end of the complete cable; a complementary band to engage said tapered threads to clamp the cable within said slotted sleeve portion and means to connect separate conductors to said first and third named metallic sleeves.

75 7. A connector for concentric electric cables comprising, in combination: means having a central opening for passage of an axial conductor of the cable and means to connect separate conductors electrically to the successive concentric layers of the cable, a casing comprising a disc having openings for passage of said axial and said separate conductors, and a cylinder to receive said connecting means and the end of the cable in connected relation, and means to connect said disc to an end of the cylinder in connector-enclosing position.

HAROLD J. C. PEARSON. 150
